UNITED STATES PATENT OFFICE

LOUIS H. McINNIS, OF BRANDON, TEXAS

TIE HOLDER

Application filed January 17, 1931. Serial No. 509,503.

This invention relates to new and useful improvements in tie holders.

The primary object of this invention is to provide a tie holder capable of holding a neck tie in a neat and proper position to the collar of the wearer thereof.

A further object of this invention is to provide a tie holder around which a four-in-hand tie may be knotted and the tie holder, with the tie thereon, may be engaged with the collar and held firmly in position by means of an invisible fastening device, similar in shape to a tie-clasp, which is attached to and a part of the lower end of the tie holder, and is made to hold the tie in position by fastening the tie holder, with the tie thereon, firmly to the bosom of the shirt approximately two and one half inches below the collar button, thus eliminating the necessity of passing the tie under the collar and round the neck.

Another object of the invention is to provide a tie holder that will be completely concealed when it is being worn and thus give the tie the appearance of having been passed around the neck and tied in the usual way.

Still another object of the invention is to provide a tie holder on which a tie may be quickly and smoothly knotted and remain tied, requiring no removal from the tie holder unless the tie becomes soiled, and then it can be easily and quickly removed from the tie holder and cleaned.

Still another object of the invention is to save fabrics in the manufacture of ties as it will require one third less silk, and still extend lower in front, when worn, than ties will that are made to go around the neck.

Other objects and advantages of the tie holder will become apparent during the study of the following description taken in connection with the accompanying drawings wherein:

Figure 1 is a front elevational view showing the holder and the tie associated therewith and both as applied to the collar of the shirt.

Figure 2 is a plan view of the knotted

portion of the tie illustrating the same as applied to the tie holder.

Figure 3 is a transverse sectional view taken substantially on the line 3—3 of Figure 1.

Figure 4 is a perspective view looking at the front of the holder.

Figure 5 is a view similar to Figure 4 viewing the holder from the rear thereof.

Figure 6 is a perspective view viewing the holder from the front thereof for more clearly illustrating the manner of substantially concealing the holder by the tie knotted thereon.

Figure 7 is a view similar to Figure 5, the tie being shown in full line with the inner skirt of the tie in engagement with the hook on one end of the clasp forming part of the holder.

With reference more in detail to the drawings, it will be seen that the tie holder is substantially T-shaped, and may be made of celluloid, metal or any other suitable and resilient material. The tie holder includes a shank 5 having integral with the upper end thereof the transverse head 6, the latter being arcuate having a concaved upper edge and a convex lower edge, the head member 6 being bowed longitudinally to provide oppositely extending wings adapted to be received beneath the wings of the collar between said wings of the collar and the neck band of the collar as suggested in Figure 1.

The shank 5 at the lower end thereof is provided with a clasp adapted to engage the shirt to secure the tie holder in position. In providing the clasp referred to, the shank 5 at the lower end thereof is provided with an integral lateral extension constituting a fixed jaw 7 for the clasp. The jaw 7 at one end thereof is provided with an inwardly directed extension serrated to provide teeth 8. A pivoted jaw 9 is pivotally engaged with the jaw 7 through the medium of a spring pivot 10 the spring 11 of which has opposite end portions contacting the jaws 7 and 9 for normally urging the teeth 8 and 12 respectively of the jaws into engagement with an edge portion of the shirt bosom as suggested in Figure 3.

Jaw 7 remote from its toothed end is provided with a prong 13 for a purpose hereinafter made manifest.

In actual practice, a four-in-hand tie herein designated generally by the reference character T is knotted about the holder in a manner well known in the art, and as suggested in Figures 4 to 7. The aprons a, b of the knotted tie will thus extend downwardly longitudinally and conceal the lower portion of the shank 5. One edge portion of the inner apron a may be then engaged with the prong 13 as clearly suggested in Figures 3, 5 and 7 to insure this apron portion a always being positioned as to obscure the clamp. The apron a of the tie being thus engaged with the clamp portion of the tie holder, will retain the apron from being thrown about as to expose the holder.

20 The tie being thus applied to the holder, the extended end of the wings of the head 6 may be then slipped in under the wings of the collar C of shirt S as shown in Figure 1 thus positioning the knot of the tie prop-

25 erly between the confronting edges of the outer wings of the collar. The jaws 7 and 9 of the clamp on lower end of shank 5 are adapted to engage with the edge of the shirt bosom as suggested in Figure 3 thus securely

30 retaining the holder in position.

It is thought from the foregoing description, taken in connection with the accompanying drawings that a clear understanding of the operation, construction, utility and advantages of an invention of this character will be had by those skilled in the art without a more detailed description thereof.

Even though I have herein shown and described the preferred embodiment of the invention, it is to be understood that the same is susceptible to changes, modifications and improvements coming within the scope of the appended claims.

Having thus described my invention, what

45 I claim as new is:

1. A tie holder comprising in combination a shank provided adjacent one end thereof with a jaw having teeth extending at right angles to the shank adjacent one edge of the shank, a second jaw pivotally connected with the first mentioned jaw and provided with teeth cooperating with the first mentioned teeth, and spring means for normally urging the teeth of the jaws into cooperating clamping relation, said jaws extending transversely with respect to the shank, and said first mentioned jaw laterally of said shank and remote from said teeth being provided with a tie engaging prong.

2. A tie holder including in combination a shank provided adjacent one edge thereof with a series of teeth projecting at substantially right angles therefrom, and a lateral extension projecting from the op-

posite edge of said shank, a jaw pivoted to said shank and provided at one end with teeth cooperating with the first mentioned teeth, and said extension being provided with a tie engaging prong.

In testimony whereof I affix my signature.

LOUIS H. McINNIS.
